UNITED STATES PATENT OFFICE.

ALFRED BYK, OF CHARLOTTENBURG, GERMANY, ASSIGNOR TO GENERAL ELECTRIC COMPANY, A CORPORATION OF NEW YORK.

TELEPHONE LINE.

Application filed January 5, 1924, Serial No. 684,645, and in Germany January 30, 1923

In telephone, especially long distance telephone engineering, it is often very important to reproduce the impedance of a line. Loaded lines can be reproduced as such by means of circuit elements connected on the other side of the inserted apparatus, such for example as amplifiers, on the artificial line side and this reproduction is facilitated as much as possible by allowing the long line to begin at a suitable point of the periodic interval. If the ohmic resistance of the real line is disregarded, which is permissible for all practical purposes, the line can be extended by means of a condenser connected in parallel with it. Küpfmüller in German Patent No. 330,964 proposed a change of the real line exceeding the mere choice of its starting point within the periodic interval. By connecting an oscillating circuit and a self-inductance at the end of the real line he changed its impedance into that of a homogeneous line the real part of which is independent of frequency. Now the kind of change leading to homogeneous lines is obviously important, but there is no basis for making an exact reproduction. The object of my invention is to obtain, with the same number of circuit elements especially for higher frequencies, a much more exact reproduction than that obtained by Küpfmüller, if we disregard the demand for provisions for homogeneity which is unimportant for the purpose at hand.

The novel features which I believe to be characteristic of my invention are set forth with particularity in the appended claims. My invention itself, however, will best be understood by reference to the following description taken in connection with the accompanying drawing, in which Fig. 1 shows diagrammatically one embodiment of my invention, and Figs. 2 and 3 show characteristic curves of telephone lines illustrating the improvement which may be obtained by means of my invention.

Let us start with the loaded line, which is ordinarily used, beginning with half the distance between coils, a line whose ohmic resistance we can practically neglect as a rule.

According to K. W. Wagner (Archiv. f.

Elektr. V. II, 1919, p. 76), this has pure real impedance,

$$W = \frac{L_o \cdot w_o}{2} \cdot \frac{1}{\sqrt{1 - \left(\frac{w}{w_o}\right)^2}} \quad (1)$$

55

if we insert the cut off frequency,

$$w_o = \sqrt{\frac{4}{L_o C_o}} \quad (2)$$

60

L_o indicates the total self-induction, C_o the total capacitance of a complete section of a line, w , 2π times the frequency. This impedance must be changed so that the frequency dependence of the real part can be reproduced as exactly as possible by a small number of elements at the artificial side of the line, whereby the imaginary part of the impedance must disappear as before for all frequencies. The change in the frequency dependence of the real part is effected by means of a shunt condenser Q of suitable capacity connected to a loaded line A as shown in Fig. 1, while the undesirable imaginary impedance part, caused by this connection, is compensated by an oscillating circuit $C_1 L_1$ at the side of the real loaded line. When the shunt condenser has suitable dimensions the real impedance of the changed line can be reproduced by an ohmic resistance R_2 , on the artificial line side, which is connected in parallel with a capacitance C_2 and a self-inductance L_2 in series. Since this connection on the artificial side of the line produces a new imaginary impedance-component, the oscillating circuit $C_1 L_1$ on the real side of the line will have to be calculated so that it not only compensates the imaginary component of the impedance introduced by the shunt condenser, but will also reproduce at the same time in the real line the imaginary component of the impedance of the reproduction $R_2 C_2 L_2$.

The impedance M of the loaded line supplemented by the shunt condenser Q with the impedance

$$-\frac{i}{Q \cdot w}$$

95

is as follows:

$$M = \frac{\frac{1}{W} - \frac{Q \cdot w}{W^2 + (Q \cdot w)^2}}{\frac{1}{W^2 + (Q \cdot w)^2} - \frac{1}{W^2 + (Q \cdot w)^2} \cdot i} = a - bi \quad (2)$$

100

if the real and imaginary parts are simplified. Inserting the value of $\bar{W}$ from (1) we have: ance can be produced by means of the following data:

$$5 \quad -bi = -\frac{1}{4} \cdot \frac{Q \cdot L_o^2 \cdot w_o^2 \cdot w}{1 - \left[\frac{1}{w_o^2} - \left(\frac{L_o \cdot w_o \cdot Q}{2} \right)^2 \right] w^2} \cdot i$$

Insert:

$$10 \quad Q = y \cdot C_o = \frac{4y}{L_o \cdot w_o^2} \quad (3)$$

and we have:

$$15 \quad -bi = -\frac{L_o \cdot y \cdot w}{1 - \frac{w^2}{w_o^2} (1 - 4y^2)} \cdot i \quad (4)$$

If we choose $y < \frac{1}{2}$ we have $1 - 4y^2 > 0$, and bi has the form of the impedance of an oscillating circuit, which is, as is well known, as follows:

$$\frac{L \cdot w}{1 - L \cdot C \cdot w^2} \cdot i$$

25 If we use: $L = L_o \cdot y$

$$L \cdot C = \frac{1 - 4y^2}{w_o^2} \quad (5)$$

or

$$30 \quad C = \frac{1 - 4y^2}{y} \cdot \frac{1}{L_o \cdot w_o^2} \quad (6)$$

the oscillating circuit L, C on the real side, will exactly compensate the imaginary impedance $-bi$ introduced by the shunt condenser.

The real part of the impedance of the loaded line supplemented by Q is, according to (2):

$$40 \quad a = \frac{\frac{L_o \cdot w_o}{2} \cdot \sqrt{1 - \frac{w^2}{w_o^2}}}{1 - \frac{w^2}{w_o^2} (1 - 4y^2)} \quad (7)$$

45 For $y = \frac{1}{2}$ whereby the denominator of (7) equals 1, a decreases as the frequency increases and the same relation obviously occurs when

50 from smaller values y approaches the value $\frac{1}{2}$.

A real part of the impedance of this kind, which decreases with the frequency can be reproduced by a suitably calculated circuit

55 $R_2 C_2 L_2$ of Fig. 1. Tests show that the best reproduction of the real part of the imped-

$$R_2 = \frac{L_o \cdot w_o}{2} \quad (8)$$

$$C_2 = \frac{0.428}{L_o \cdot w_o^2} \quad (9)$$

$$w_2 = 1.075 \cdot w_o \quad (10)$$

$$Q = \frac{1.44}{L_o \cdot w_o^2} \quad (11)$$

Here

$$70 \quad w_2 = \frac{1}{\sqrt{C_2 \cdot L_2}}$$

indicates the natural frequency of the oscillating circuit composed of C_2 and L_2 .

Due to the imaginary impedance part introduced with the circuit $R_2 L_2 C_2$ the oscillating circuit $L_1 C_1$, as assumed previously in Equations (5) and (6) has to be altered. It is found that this oscillating circuit, in addition to compensating the imaginary impedance part of the loaded line supplemented by Q also performs the necessary reproduction of $R_2 L_2 C_2$ if one uses the following equations with (8) to (11):

$$75 \quad L_1 = 0.240 \cdot L_o \quad (12)$$

$$80 \quad C_1 = \frac{1.73}{L_o \cdot w_o^2} \quad (13)$$

85 Equations (8) to (13) represent the total changing and reproduction of the loaded line as functions of L_o and w_o .

The efficiency of the reproduction produced according to the arrangement in Fig. 1 might be tested with a series of frequencies by calculations for the Rhineland cable, for which:

$$90 \quad R_o = 27 \Omega, L_o = 0.24 \text{ henry},$$

$$w_o = 16013 \text{ sec}^{-1} \quad (14)$$

(R_o is the ohmic resistance of a complete periodic interval of the cable.) For the sake of comparison let us also compute the reproduction of the cable according to Küpfmüller's method, mentioned above.

Taking into consideration the ohmic resistance the impedance of the loaded cable beginning with half the distance between coils is (see K. W. Wagner, l. c.):

$$105 \quad W' = \sqrt{\frac{R_o + iL_o \cdot w_o}{i \cdot C_o \cdot w}} \cdot \frac{1}{\sqrt{1 + \frac{1}{4} i C_o \cdot w (R_o + iL_o \cdot w)}} \quad 110$$

With the quantity ratios concerned, this might be written according to Küpfmüller as follows (see 1. c., p. 2):

$$5 \quad W' = \sqrt{\frac{\frac{L_o}{C_o}}{1 - \left(\frac{w}{w_o}\right)^2} - \frac{R_o}{\left[1 - \left(\frac{w}{w_o}\right)^2\right]^2} \cdot i} \quad (15)$$

10 If, however for the changing of (15) Küpfmüller uses the following approximation formula:

$$15 \quad \frac{1}{1 - \left(\frac{w}{w_o}\right)^2} = 1 + \left(\frac{w}{w_o}\right)^2 \quad (16)$$

it is not permissible for the frequency range concerned for all practical purposes, because

20 for $\frac{w}{w_o} = 0.9$, a value which is prominent as a limit for balancing the impedance, it is for instance

$$25 \quad \frac{1}{1 - \left(\frac{w}{w_o}\right)^2} = 5.26$$

whereas

$$1 + \left(\frac{w}{w_o}\right)^2 = 1.81$$

30 which means that one side of Equation (16) is about three times larger than the other.

The absolute value of the quotients of the imaginary and real parts under the radical in (15)

$$A = \frac{R_o}{w_o \cdot L_o \left(\frac{w}{w_o}\right) \cdot \left(1 - \frac{w^2}{w_o^2}\right)} \quad (17)$$

40 is so small for all values of w which have to be

$$W' = \frac{L_o \cdot w_o}{2} \cdot \frac{1}{\sqrt{1 - \frac{w^2}{w_o^2}}} - \frac{R_o}{4} \cdot \frac{w_o}{w} \cdot \frac{1}{\left(1 - \frac{w^2}{w_o^2}\right)^{\frac{3}{2}}} \cdot i = d - gi \quad (19)$$

if simplifications are made for the real and imaginary parts of W' .

After switching in any kind of a shunt con-

$$W'' = \frac{-(d - gi) \cdot \frac{i}{K \cdot w}}{(d - gi) - \frac{i}{K \cdot w}} = \frac{d}{(d \cdot K \cdot w)^2 + (1 + g \cdot K \cdot w)^2} - \frac{d^2 k \cdot w + g + g^2 k \cdot w}{(d k \cdot w)^2 + (1 + g \cdot K \cdot w)^2} \cdot i$$

or, if we insert:

$$W'' = \frac{d \cdot h}{1 + (d \cdot K \cdot w)^2} - \frac{d^2 k \cdot w \cdot h + g \cdot h + g^2 k \cdot w \cdot h}{1 + 2g \cdot K \cdot w \cdot h + (gk \cdot w)^2 h} \cdot i$$

If, as is permissible, terms higher than the first power of A or R_o or g are disregarded, this gives the following:

$$W'' = (dh - 2g \cdot K \cdot w \cdot d \cdot h^2) - (d^2 k \cdot w \cdot h + g \{h - 2k^2 \cdot w^2 \cdot h^2 d^2\}) i \quad (20)$$

taken into account that we can practically disregard its higher powers. At the limits of the frequency range concerned $\frac{w}{w_o} = 0.2$ and

$\frac{w}{w_o} = 0.9$, A is 0.0366 or 0.0411, that is, sufficiently small. One can easily be convinced that A assumes no larger values in the intermediate range. The extreme of A is of course expressed by the condition:

$$\frac{d}{d \left(\frac{w}{w_o}\right)} \left[\frac{w}{w_o} \left(1 - \frac{w^2}{w_o^2}\right) \right] = 1 - \frac{3w^2}{w_o^2} = 0$$

or

$$\frac{w}{w_o} = \sqrt{\frac{1}{3}} = 0.577$$

This extreme represents a minimum of A since for $\frac{w}{w_o} = 0$ and $\frac{w}{w_o} = 1$, A is infinitely large.

Within this range which has a minimum as the only extreme, A can assume no larger value, however, than the largest of its two values at the limits of the range in question.

Neglecting the higher powers of A , (15) can be written:

$$70 \quad W' = \sqrt{\frac{L_o}{C_o \left(1 - \frac{w^2}{w_o^2}\right)}} \cdot \left(\cos \frac{\varphi}{2} - i \sin \frac{\varphi}{2}\right) \quad (18)$$

whereby $\varphi = \text{arc tan } A$

or

$$\sin \left(\frac{\varphi}{2}\right) = \frac{\varphi}{2} = \frac{A}{2}; \cos \frac{\varphi}{2} = 1$$

are true.

Introduced into (18):

80

85

denser Q the loaded line has the following impedance:

85

Fig. 2, curve I shows the path of the real part of the impedance of the Rhineland cable changed according to the present invention by a shunt condenser and oscillating circuit, 5 as a function of $\frac{w}{w_0}$, Fig. 2, curve II shows the path of the corresponding reproduction. Fig. 2, curves III and IV illustrate, with the sign altered, the imaginary part of the impedance of the changed cable as well as the imaginary part of the impedance of the reproduction. Fig. 3, curves I to IV give the corresponding magnitudes for the Rhineland cable reproduced according to Küpfmüller's method (shunt condenser $K_o = 0.315C_o$, oscillating circuit of the change, $L'_1 = 0.315L_o$,

$$C'_1 = 0.57 \frac{1}{L'_1 \cdot w_0^2}$$

20 self-inductance of the change

$$L' = \frac{R_o}{4w_0}$$

25 ohmic resistance of the reproduction

$$= \sqrt{\frac{L_o}{C_o}}$$

capacitance of the reproduction,

$$= \frac{4}{R_o \cdot w_0}$$

30 The graphic representation shows plainly the superiority of the method described here in comparison with Küpfmüller's, especially with higher frequencies.

TABLE.—Comparative reproduction error.

	According to this invention	According to Küpfmüller	
		Per cent	Per cent
$\frac{w}{w_0} 0.2$	2.8	0.23	
$\frac{w}{w_0} 0.4$	1.7	0.74	
$\frac{w}{w_0} 0.6$	1.0	1.3	
$\frac{w}{w_0} 0.8$	3.4	3.7	
$\frac{w}{w_0} 0.9$	5.9	17.6	

40 In the above table the comparative error 55 in reproduction made according to the method described here and according to that given by Küpfmüller is recorded. If Z is the complex impedance of the total changed line on the real side, and N that of the reproduction on the artificial side, the following equation represents the comparative reproduction error:

$$60 V = \left| \frac{Z - N}{\frac{1}{2}(Z + N)} \right|$$

The superiority of this method is again evident in the values of V especially with higher frequencies.

As the calculations with the Rhineland cable show, it is usually unnecessary to consider the ohmic resistance in reproducing a line. If one wishes to do this however, in cases of especially large ohmic resistance, the imaginary part of the impedance dependent on the ohmic resistance may be compensated by a self-inductance and capacitance.

What I claim as new and desire to secure by Letters Patent of the United States, is,—

1. In a telephone line loaded with inductances, an arrangement for changing the impedance of the line to facilitate impedance simulation, said arrangement comprising means to build out the terminal of the line to a fraction of a section intermediate between a mid section and a full section so that the real part of the impedance of the line may be simulated by the real part of the impedance of a network comprising resistance shunted by capacity and inductance in series, and compensating means connected to the terminal of the line, said compensating means being such that its impedance has no real component and its imaginary component compensates for the difference between the imaginary components of the impedances of the built out line and simulating network, respectively.

2. In a telephone line loaded with inductances, an arrangement for changing the impedance of the line to facilitate impedance simulation, the said arrangement comprising a capacity shunted across the terminal of the line to build out the terminal of the line to a fractional section intermediate between a mid section and a full section so that the real part of the impedance of the line may be simulated by the real part of the impedance of a network comprising resistance shunted by capacity and inductance in series, and compensating means connected to the terminal of the line, said compensating means being such that its impedance has no real component and its imaginary component compensates for the difference between the imaginary components of the impedances of the built out line and simulating network, respectively.

3. In a telephone line loaded with inductances, an arrangement for changing the impedance of the line to facilitate impedance simulation, said arrangement comprising means to build out the terminal of the line to a fraction of a section intermediate between a mid section and a full section so that the real part of the impedance of the line may be simulated by the real part of the impedance of a network comprising resistance shunted by capacity and inductance in series, and compensating means in series with the line at the terminal thereof, said compensating means comprising an oscillating circuit whose im-

pedance has no real component and the imaginary component of whose impedance is such as to compensate for the difference between the imaginary components of the impedances of the built out line and simulating network, respectively.

4. In a telephone line loaded with inductances, an arrangement for changing the impedance of the line to facilitate impedance simulation, said arrangement comprising a capacity shunted across the terminal of the line to build out the terminal to a fraction of a section intermediate between a mid section and a full section so that the real part of the impedance of the line may be simulated by

the real part of the impedance of a network comprising a resistance shunted by capacity and inductance in series, and compensating means in series with the line at the terminal thereof, said compensating means comprising an oscillating circuit whose impedance has no real component and the imaginary component of whose impedance is such as to compensate for the difference between the imaginary components of the impedances of the built out line and simulating network, respectively. 20

In witness whereof, I have hereunto set my hand this 12th day of December, 1923.

ALFRED BYK.

Certificate of Correction.

Patent No. 1,694,248.

Granted December 4, 1928, to

ALFRED BYK.

It is hereby certified that error appears in the printed specification of the above numbered patent requiring correction as follows: Page 3, lines 13 to 15, for the formula

$$\frac{1}{1 - \left(\frac{w}{w_o}\right)} = 1 + \left(\frac{w}{w_o}\right)^2 \quad (16)$$

read

$$\frac{1}{1 - \left(\frac{w}{w_o}\right)^2} = 1 + \left(\frac{w}{w_o}\right)^2 \quad (16)$$

Same page, lines 23 to 25, for formula

$$\frac{1}{1 - \left(\frac{w}{w_o}\right)} = 5.26$$

read

$$\frac{1}{1 - \left(\frac{w}{w_o}\right)} = 5.26$$

and that the said Letters Patent should be read with these corrections therein that the same may conform to the record of the case in the Patent Office.

Signed and sealed this 15th day of January, A. D. 1929.

[**SEAL.**]

M. J. MOORE,
Acting Commissioner of Patents.
